UNITED STATES PATENT OFFICE.

EDWARD J. WORCESTER AND ALBERT F. PRENTICE, OF WORCESTER, MASSACHUSETTS, ASSIGNEES TO ALBERT F. PRENTICE, VERNON F. PRENTICE, AND IRA W. JONES, OF SAME PLACE.

IMPROVEMENT IN DRILLING-MACHINES.

Specification forming part of Letters Patent No. 127,132, dated May 21, 1872.

To all whom it may concern:

Be it known that we, EDWARD J. WORCESTER and ALBERT F. PRENTICE, both of the city and county of Worcester and Commonwealth of Massachusetts, have invented certain new and useful Improvements in Drills; and we do hereby declare that the following is a full, clear, and exact description of the same, reference being had to the accompanying drawing which forms a part of this specification, and in which—

Figure 1 represents a front view of our improved drill, and Fig. 2 represents a side view of the same.

The nature of our invention consists in the combination and relative arrangement with the supporting-frame and drill-spindle of driving and regulation shafts, operating gears, and balance-wheel, all constructed and arranged for operation as shown in the accompanying drawing and hereinafter described.

On the drawing, the part marked A represents the frame. B indicates the drill-spindle, which is supported in the bearings *a a*. C indicates the feeding-screw, connected to the upper end of the spindle B by a loose coupling, C', and arranged through the center of a revolving quill, D, which is supported in the bearing *b* at the upper part of the frame. The screw C is prevented from turning by a pin, *c*, which projects from the rear side of the screw and works in a groove on the frame A, while the quill D is revolved by the action of the pawl *d* upon its ratchet-wheel D', and serves as a nut upon the screw C for moving the drill-spindle B. E indicates the crank-shaft, from which motion is transmitted to the drill-spindle B by means of the bevel-gears F F'; the latter being connected with the spindle B by a spline and groove. Shaft E is supported in the bearings *a' a'*, and is provided with a crank, E', which crank can be adjusted to a greater or less length to increase or diminish

its leverage, as speed or power may be desired. G indicates a balance-wheel for regulating the power and giving momentum to assist in carrying the crank past the dead-points. The balance-wheel G is mounted on one end of a short shaft, K, arranged through the bearing *f* and frame A, and having its opposite end connected for operation to the crank-shaft by means of the spur-pinion I and gear H, as shown. L indicates the lever for operating pawl *d* and ratchet D'; said lever is fulcrumed on a projecting portion, *g*, of the frame A, and is actuated by a cam, M, on the crank-shaft, substantially as in the ordinary manner.

By constructing and arranging the parts as herein shown and described a very compact and convenient drill is produced, and one which is quite easy of operation, as the balance-wheel G, which revolves rapidly, greatly assists in carrying the crank past the dead-points, and thus enables the operator to run the drill with a steady and uniform motion, while, at the same time, by arranging the spur-gears H I and bevel-gear F upon one side of frame A and the balance-wheel G upon the other side of said frame, but little space, comparatively, is taken up or occupied outside of the frame A by the mechanism for giving motion to and regulating the action of the drill-spindle B.

Having described our improved drill, what we claim therein as new and of our invention, and desire to secure by Letters Patent, is—

The combination, with the frame A and drill-spindle B, of shafts E K, gears F F' H I, and balance-wheel G, said parts being constructed and arranged in relation to each other, substantially as shown and described.

EDWARD J. WORCESTER,
ALBERT F. PRENTICE.
